IRONING MACHINE.

Application filed April 17, 1925. Serial No. 25,279.

Our invention relates to ironing machines and an object of our improvements is to provide an effective machine that is simple in construction, light in weight, that occupies but little floor space; and one that will move the material over a heated iron shoe at the same time keeping the material in contact with the shoe, that will permit closing and opening the shoe independently of the rotation of the feed roll, thus allowing the material to be pressed between the feed roll and the shoe without being mechanically moved across the surface of the shoe; and one that is adapted to iron or press tubular garments or materials, in other words, a machine that has a full open end feed roll.

We secure these advantages and others in the apparatus shown in the accompanying drawings, in which

20 Figure 1, is an elevation, mostly in detail longitudinal vertical section of an apparatus embodying our invention.

Figure 2, is a section on the line II—II looking in the direction of the arrows.

25 Figure 3, is a plan view, the feed roll, its supporting tube, the shoe, table and guiding means and the feed roll actuating mechanism being removed.

Figure 4, is a detail sectional view on the 30 line 4—4 of Figure 1, looking in the direction of the arrows; the feed roll and the actuating sprocket wheel therefor being removed.

Figure 5, is a detail sectional view showing the connection of the actuating rods to the 35 shoe.

Figure 6, is a detail elevation of the right hand end of the tube d , as shown in Figure 1.

Figure 7, is a detail vertical section of the 40 feed roll and shoe at the left hand end thereof, as shown in Figure 1.

a , a , are the end standards or uprights; these are formed of sheet metal pressed out so as to be hollow on their inner sides thus providing a strengthening flange a^2 extending around the edge of the same. These are supported upon cast iron foot pieces e , e^2 . e^3 , indicates the casters on the foot piece e^2 . The uprights a , a , are connected toward their lower ends by the sheet metal pressed out girder construction b and at their upper ends near their front and rear edges by the sheet metal cross pieces c , c , which are L-shaped in cross section; the horizontal portion being at the lower edge and extending inward. 50 This constitutes the frame of the machine.

d , is a thin sheet metal tube, one end of which is cut and turned outward to form flanges d^2 (Fig. 6). This tube extends through an aperture formed therefor in the right hand upright a toward the top thereof 60 and the flanges d^2 engage against an arm riveted or otherwise secured to the web of the said upright at the outer surface thereof, thus the tube is held rigidly in its horizontal position, as shown in Figure 1.

f , is a shaft bearing in and extending between the foot pieces e , e^2 . Said shaft or rod connects foot pieces e and e^2 together and serves to support the pedal g , g^2 , which rocks about the same.

70 h , is a thin cylinder constituting the active portion of the feed roll. The cylinder h is provided with pressed out end pieces h^2 , h^2 which fit over collars h^4 , which collars are adapted to fit and slide axially upon the supporting cylinder d . The left hand end of the supporting cylinder d is closed by a disk d^3 fixed in the end of said cylinder.

75 j , is a sprocket wheel bearing and adapted to turn upon the cylinder d at its right hand end adjacent to the web of the upright a . j^2 , j^2 , are pins extending axially inward from the surface of the sprocket wheel j near the periphery thereof and engaging in apertures h^3 in the right hand end piece h^2 of the cylinder h . h^5 , is a thin metal disk.

80 The sprocket wheel j is first slid into position along the surface of the supporting cylinder d , then the feed roll h is placed in position, as shown in Figure 1 so that the pins j^2 85 engage through the apertures h^3 . The disk h^5 is then placed in position and secured therein by a thumb screw d^4 engaging through said disk and into the closure d^3 or by other suitable means, thus securing the feed roll in 90 engaged position so that it may be easily detached.

95 k , is a casing of box-like form having its open end engaging against the inner surface of the upright a at the right of the apparatus, 100 as shown in Figure 1. The web of said upright serves to close the open end of said casing. k^2 , is a cylindrical spindle or arbor extending from the wall of the casing k within said casing.

105 m , is a sleeve engaging the spindle k^2 and adapted to rotate thereon. m^2 , indicates sprocket wheel teeth upon the sleeve m . m^3 , is a worm wheel upon the sleeve m . n , is a worm engaging the teeth of the wheel m^3 . 110

p, is a pulley on the outer end of the worm *n*. *o*, is an electric motor secured to the inner surface of the upright *a* below the casing *k*. *po* is a belt passing around a pulley on the shaft of the motor *o* and around the pulley on the worm *n*.

m²j is a sprocket chain engaging the teeth of the sprocket wheel *m²* and of the sprocket wheel *j*. The feed roll *h* may be driven by 10 the motor *o* through the gearing just described.

g, is the ironing shoe, this has an arcuate form in cross section at its upper surface to correspond to the form of the feed roll *h*. 15 The shoe *g* is preferably of cast metal and is provided with a central longitudinal conduit or passage *g²* from which extends laterally in both directions small apertures *g³*.

The gas is supplied through the pipe *g⁵* 20 (Fig. 1) to the passage *g²* and passes out through the apertures *g³* in both directions where it is lighted and burns to heat the shoe *g*. *g⁷*, is a sheet metal hood secured to the lower surface of the shoe *g* and extending 25 over the jets of burning gas coming from the apertures *g³*.

There are four sockets *g⁴* formed in the under surface of the shoe *g* at its four corners. In each of these sockets is placed a piece of 30 thin tubing *t²* with its upper end closed and its lower end open.

A circular aperture is formed through the horizontal flange of a cross piece *c* axially in line and below each of the sockets *g⁴*. In each 35 of said apertures is placed a cup *t* having its lower end closed and its upper end turned over in a flange engaging upon the upper surface of the cross piece *c*. Each of the tubes *t²* extends at its lower end into the cup *t* and 40 is adapted to slide axially therein. There is a spring *u* resting at its lower end within and upon the lower end of each of the cups *t* and engaging at its upper end against the upper end of a tube *t²*. The springs *u* act to force 45 the shoe *g* yielding toward the feed roll *h*.

v, is a table extending between the uprights *a* in position to receive the articles to be ironed or pressed before they pass under the feed roll. *w*, is a sheet metal guide extending 50 back of the machine in position to receive the articles as they pass out from beneath the feed roll and this is extended below the shoe *g* and under the same to a delivery point *w²* under the table *v* at the front of the machine 55 where the operator may receive the articles that have been through the machine.

r, is a lever pivoted to the foot piece *q²* and adapted to oscillate in a horizontal plane. This is turned upward at its end inside of 60 the foot piece *q²* so that it may be easily actuated by the foot of the operator. *s*, is a bolt that may normally be pulled forward by the spring *s²* and when in this position engage under a ledge *e⁴* on the foot piece *e*. By rocking 65 the lever *r*, the bolt *s* is withdrawn by

means of the connecting rod *rs* to disengage it from the ledge *e⁴*.

q, q, are four rods connected at their lower ends to the oscillating pedal construction *q*, *q²* and at their upper ends engaging the shoe 70 *g* at its four corners, as shown at *g⁶*, (Fig. 5.)

By pressing down upon the foot piece *q²*, the shoe *g* is drawn downward away from the feed roll *h* and may be secured in this 75 position by the bolt *s*. When the bolt *s* is released by the foot of the operator, the pedal piece *q²* rises being controlled by the pressure of the foot of the operator, allowing the springs *u* to press the shoe *g* upward and 80 against any article that may have been placed between said shoe and the feed roll *h*.

The apparatus as shown and described, is intended primarily for domestic household use, but may be enlarged for other uses. 85

In the size for this purpose, the whole apparatus will weigh in the neighborhood of 100 pounds and the entire length is only about two inches more than the length of the ironing shoe. The material to be acted upon is usually fed in the usual way between the rotating cylinder *h* and the shoe *g*, but articles of tubular form may be placed over the roll *h* by sliding them axially over said roll from the left hand side, as shown in Figures 1 and 90 7. Articles may be pressed by depressing the shoe, placing the article upon the upper surface of the shoe and then allowing the shoe to rise, then moving the shoe down again and moving the article along and repeating 95 the operation.

It will be observed that the shoe *g* has a resilient floating support so that it may adjust itself to unequal thicknesses of material above it or between it and the feed roll. 100 That the connection between the actuating device and the shoe *g* is simple and direct so that the shoe may be pulled directly downward and allowed to rise directly upward with a control motion.

What we claim is:—

1. In an apparatus of the kind described, a frame, a feed roll in the upper part of said frame, a pedal apparatus at the lower portion of said frame, a shoe in said frame extending beneath said feed roll, guides for said shoe, said shoe being adapted to move vertically, said pedal apparatus being connected immediately to said shoe to draw said shoe downward, and a spring resting upon said frame and acting to force said shoe upward and supporting said shoe. 115

2. In an apparatus of the kind described, a frame, a feed roll in the upper part of said frame, a pedal apparatus at the lower portion of said frame, a shoe in said frame extending beneath said feed roll, guides for said shoe, said shoe being adapted to move vertically, said pedal apparatus being connected to said shoe to draw said shoe downward, and 125 130

a plurality of springs horizontally spaced from each other acting upon said frame and acting to force said shoe upward at their respective positions and supporting said shoe.

5. 3. In an apparatus of the kind described, a frame, a feed roll in said frame, a shoe in said frame extending beneath said feed roll, a plurality of springs horizontally spaced from each other acting upon said frame and 10 acting to force said shoe upward at their respective positions and supporting said shoe, and means for retracting said shoe immediately engaging the shoe.

4. In an apparatus of the kind described, 15 a frame, a feed roll in said frame, a shoe in said frame extending beneath said feed roll, a plurality of springs horizontally spaced from each other in two directions, supporting said shoe and acting to force said shoe 20 upward at their respective positions.

5. In an apparatus of the kind described, a standard, a supporting tube d secured at one end to said standard and extending horizontally therefrom, a feed roll h adapted to be 25 slid over said tube and to be actuated from its inner end, a filling piece d^s in the outer end of said tube, and a disk h^s engaging the outer end of said feed roll and tube and se-

cured to said filling piece, substantially as shown and described. 30

6. In an apparatus of the kind described, having a frame, the combination of a shoe, a tubular construction secured to said shoe, a fixed cup-like construction secured to said frame, said tubular construction fitting and 35 adapted to slide in said cup-like construction, and a spring enclosed in said cup-like and tubular construction and bearing at the outer ends of said constructions.

7. In an apparatus of the kind described, 40 two sheet metal standards, a sheet metal cross piece extending between said standards and having an L-shape in cross section, a shoe extending above the horizontal portion of said cross piece and having a socket therein opening from the lower surface thereof, the horizontal portion of said cross piece having an aperture therethrough axially in line with said socket, cup shaped parts in said socket and aperture adapted to slide within each 45 other and a spring within said parts.

In testimony whereof, we sign this specification.

LAWRENCE W. FISCHER.
